UNITED STATES PATENT OFFICE.

EUGEN MARSCHNER, OF WEISSENSEE, NEAR BERLIN, GERMANY, ASSIGNEE TO GLEICH-
RICHTER-GESELLSCHAFT M. B. H., OF BERLIN, GERMANY, A CORPORATION OF
GERMANY.

MERCURY-VAPOUR ARC RECTIFIER OF GLASS.

Application filed August 30, 1921, Serial No. 497,058, and in Germany May 27, 1919.

(GRANTED UNDER THE PROVISIONS OF THE ACT OF MARCH 3, 1921, 41 STAT. L., 1313.)

This invention has reference to mercury vapor-arc rectifiers of glass and especially to an electrode insertion for this kind of rectifiers.

5 With such electrode insertions difficulties result with great current intensities. The platinum insertions generally known can for security of service only be made up to wire thicknesses of 2 to 2.5 mm. so that, with 10 such current intensities, several wires mounted in parallel have to be used. This arrangement has the drawback that a uniform distribution of current can only be obtained with difficulty and that the fusions can 15 easily be disrupted, owing to overloading of the individual wires.

In contradistinction to this the subject of this invention is an electrode insertion, use being made of a small platinum pot, 20 closed off from the vacuum vessel, in a similar manner as already known in connection with Röntgen tubes. In comparison with the simple conditions prevailing with Röntgen tubes in the case of vacuum vessels, however, for mercury vapor-arc rectifiers, there 25 must still be added the difficulties which are caused by the mercury, and this necessitates a deviation from the usual construction of the platinum pot.

30 The drawing shows constructional examples of the invention.

Figure 1 is a longitudinal section through an electrode insertion, in which the electrode is an anode.

35 Figure 2 shows a similar longitudinal section through an electrode insertion, where the electrode is a cathode.

Figure 3 shows, upon a largely increased scale, a partial section through a modified constructional form.

In Figure 1 *a* is the glass body which is turned over towards the inside at its open end. In this fold there is now fused in a small pot *b* of thin sheet platinum or of a 40 platinum alloy. Owing to the density of the platinum this pot affords a certain and reliable air seal. The pot *b* has a contacted neck *f* and a bottom *d*. Upon this bottom there is welded or soldered at one side the

conductor *c* to the anode *g* and, on the other side, the conductor *g* for the current to the glass body. The thinness of the walls combined with the diminutiveness and shape of the pot, permits of the compensation by the 50 pot itself of all the mechanical stresses produced by the unequal heating of the anode and prevents any injury to the points of fusion. The conductor *c* to the electrode or to the anode *e* consists of a metal, such as nickel for instance, which does not amalgamate with mercury but which can be 55 easily welded to platinum. A hard soldering of another metal, such for instance as iron which cannot be welded to platinum, is of no use, as the soldering point would 60 then be quickly destroyed by the mercury. In the narrow neck *f* of the platinum pot there is soldered a strong lead *g* of a metal, such as copper for instance, which is a good conductor of heat and electricity. The 65 soldering is effected preferably with silver or other similar hard solder. In this way the feed of current takes place with safety without breaking through the platinum layer. To improve the radiation of heat to 70 the surrounding air the lead *g* is provided with several ribs *h* of sheet copper or similar metal, to which at the same time the connection for the exterior lead is effected. 75

In order to prevent oscillations or vibrations in case of shocks or tremors there is soldered upon the end of the glass body *a*, a cap *i*, in which there is provided a hollow cone into which there fits a solid cone *k*, held down upon the lead *g* by means of screws 80 and soldered together with the cap after mounting has once been effected. By such means the lead is provided with a second point of support in addition to a cooperating guide ring *m* of thin sheet iron, which is shown adjacently connected to the electrode *e*. At this point the glass vessel *a* is preferably provided with a nick, whilst at *o*, at a point which is sufficiently remote 85 from the point of soldering on the platinum pot, the end of the glass vessel can be fused together with the remaining portion of the glass vessel *a*. This type of construction 90

facilitates the connection of the platinum pot with the conductors *c* and *g*.

In the constructional form according to Figure 2 the type of the construction is substantially the same, but simpler, as the point of connection lies entirely within the mercury *p*. In place of the anode *e* a disc *q* is used as cathode. The conductor *c* could also consist of copper in both constructional forms. In this case it, together with the silver soldering, must be protected against the action of the mercury by means of a strong galvanic coating of some metal, such as iron or nickel, capable of resisting the action of mercury.

In the modified constructional form according to Figure 3 the pot *b* does not consist of platinum but of nickel, or any other metal alloy free from platinum, but it must be absolutely free from pores and its coefficient of expansion must correspond as much as possible to that of the glass. In this case the pot of nickel or other metal free from platinum must be provided at its edge, as far as it is fused into the turned over neck of the glass vessel, with a coating of pure platinum or platinum alloy which is adapted to be fused together with glass. This coating can be galvanically deposited or electrically fused onto the other part. In Figure 3 *g* is the current conductor, *c* the lead connected with the electrode, and *b* is the platinum pot made of nickel for instance in this case, whilst *a* is the glass vessel. As far as the pot *b* is fused into the glass vessel, its edge is provided with the coating of platinum *x* or the platinum alloy referred to.

Experiments have shown that an electrode insertion according to Figure 3, has the same good properties as that with the platinum pot according to Figures 1 or 2, but the high costs and difficulties connected with the use of platinum are obviated. Nickel is the most suitable material for this construction, said nickel being melted in vacuo in order to secure perfect freedom from pores. Of course in Figure 3 the coating *x* is shown in a greatly exaggerated scale for the sake of clearness.

A further constructional form of the electrode insertion according to the invention is based upon the recognition of the fact that the elastic pot, even if it does not consist of platinum, can be made without a coating of platinum or a platinum alloy at the point of insertion if, namely, use be made of a material melted in vacuo having a coefficient of expansion which corresponds to that of platinum. Nickel iron melted in vacuo, or completely pure iron which has also been melted in vacuo, has been found to be a metal pre-eminently suitable for the purpose.

What I do claim as my invention and desire to secure by Letters Patent of the United States is:—

1. A mercury arc rectifier comprising a glass vessel containing an electrode and having a leading-in portion formed with an inwardly extending neck; a cup with elastic walls of thin platinum with its open end fused into the end of said neck and closing the latter; an external conductor of electricity and heat fused to said cup and extending past the joint between the cup and said inwardly extending neck; an internal conductor which does not amalgamate with mercury extending from said electrode and also fused to said cup, thus uniting said conductors and cup in a practically integral structure; and means for supporting the external conductor independently of said cup so as to permit the use of conductor bars capable of carrying high tension currents. 85

2. A mercury arc rectifier comprising a glass vessel containing an electrode and having a leading-in portion formed with an inwardly extending neck; a cup with elastic walls of thin platinum having its open end fused to the open end of said neck forming an extension of and closing the latter; an internal conductor bar capable of carrying a high tension current and which does not amalgamate with mercury connecting said electrode with said cup and fused to the latter; an external conductor of electricity and heat fused to said cup and extending out therefrom through said neck; and means supporting the external conductor independently of said cup together with means for aligning and guiding said internal conductor within the vessel under expansions and contractions to relieve supporting strain upon the cup. 100

3. In a mercury vapor arc rectifier of glass the combination of an elastic pot of thin sheet of platinum containing metal fused into the neck turned down upon itself of the glass body with a conductor for the electrode of a metal which does not amalgamate with mercury welded upon the bottom of said pot on the inner side of the glass vessel, an outward-leading conductor of a metal which is a good conductor of electricity and heat welded in the contracted neck-shaped part of the said pot on the outer side of the glass vessel, and a conical block clamped on the outward-leading conductor and fitting into a conical opening in a member connected to the glass vessel, substantially as set forth. 115

4. In a mercury vapor arc rectifier of glass the combination of an elastic pot of thin sheet of platinum containing metal fused into the neck turned down upon itself of the glass body with a conductor for the electrode of a metal which does not amalgamate with mercury welded upon the bottom of said pot on the inner side of the glass vessel, an outward-leading conductor of a metal which is a good conductor of electricity and heat welded in the contracted neck-shaped part of the said pot on the outer side of the glass vessel, and a conical block clamped on the outward-leading conductor and fitting into a conical opening in a member connected to the glass vessel, substantially as set forth. 125

gamate with mercury welded upon the bottom of said pot on the inner side of the glass vessel, an outward-leading conductor of a metal which is a good conductor of electricity and heat, welded in the contracted neck-shaped part of the said pot on the outer side of the glass vessel, vanes on the outward-leading conductor adapted to carry off the heat and to receive the connecting means for the external leads, and a conical block clamped on the outward-leading conductor and fitting into a conical opening in a member connected to the glass vessel, substantially as set forth.

In testimony whereof I affix my signature.

EUGEN MARSCHNER.
